SEAL

Winfred M. Brooks, West Orange, N. J., assignor
to E. J. Brooks Company, Newark, N. J., a cor-
poration of New Jersey

Application December 19, 1950, Serial No. 201,662.

1 Claim. (Cl. 292—322)

1

The present invention relates to sheet material seals such as are used, for instance, for sealing bags containing seed, or as poultry seals, to guarantee the standard of the product sealed. One type of seal used for the above purpose consists of two main sections that are movable toward one another on a bending line located where they are connected together, said main sections having means at their free ends that interengage in closing the seal. Sometimes it is found, upon inspection, that the product which has been sealed is not up to the required standard, and it has been the custom, heretofore, to disengage the means at the free ends of the main sections to open the seal, and to remove it from the product previously sealed. Of course, all seals of this character can be opened and, on being opened, are either destroyed or reveal the fact that the seal has been tampered with, but the interengaging means at the free ends of the main sections are purposely constructed to render opening of the seal difficult and to make it a time-consuming operation to the one who attempts to tamper with the seal. When, however, it is desired to remove the seal after sealing the product, in cases where the standard of the product has been found to be below that which is required, it will be understood that a time-consuming process in the opening of the seal is disadvantageous because sometimes a great quantity of products has to be unsealed.

The main object of this invention is a seal so constructed as to render rupture thereof quick and easy without initially trying to untangle the locking means at the free ends of the sections.

In the accompanying drawings—

Fig. 1 is a plan view of the blank from which the seal is formed:

Fig. 2 is an edge view of the blank shown in Fig. 1.

Fig. 3 is a view in side elevation of the blank bent up preparatory to its use in the sealing operation.

Fig. 4 is a view looking in the direction of arrow 4 in Fig. 3.

Fig. 5 is a sectional view showing the seal in its closed position with the nose of the pliers in-

Fig. 6 is a view looking in the direction of arrow

Fig. 6 is a view looking in the direction of arrow 6 of Fig. 5 without indication of the pliers; and Fig. 7 is a perspective view showing the in-

Fig. 1 is a perspective view showing the insertion of the nose of a normally closed pair of pliers in the rupture-opening of the seal with the pliers expanded and the seal ruptured.

10 and 11 indicate the two main sections that

are movable toward one another on bending line 12 located where the sections are connected together. The locking means here employed to interengage, when closing the seal, consist of a tongue 13 inwardly bent over main section 11 and having an opening 14 for the reception of a prong 15 carried by main section 10, said prong having a spur 16. Main section 11 has inner and outer surfaces curved, at least in part, for the purpose of deflecting the end of prong 15 when it enters slot 14 in closing the seal, to thereby cause spur 16 to engage end 17 of tongue 13 so as to prevent retraction of the parts (see Fig. 5). Main section 10, however, is a substantially flat member, as required by commercial conditions, to facilitate the closing of the seal and to make the seal as compact as possible.

18 indicates a rupture-opening, in said main sections, that spans bending line 12 intermediate the ends thereof, said opening tapering at opposite ends as indicated at 19 and 20 in a direction at right angles to bending line 12. 19 indicates a hood formed by outwardly raising a portion of the material of flat main section 10 so that, when the seal is closed, a tool may be readily inserted in said opening for the purpose of rupturing the seal along bending line 12.

In Figs. 5 and 7 is shown the method of inserting nose 21 of a reverse plier 22, i. e. a pair of pliers that are normally held in closed position by means of a spring such as 23. After the nose of the pliers has been inserted in opening 18, the handles of the pliers are squeezed together against the opposition of spring 23, thereby separating the members of nose 21 and rupturing the seal along bending line 12. Thereafter, it is, of course, easy to separate prong 15 from engagement with tongue 13.

It is important that ends 19 and 20 of rupture-opening 18 taper in a direction at right angles to the direction of bending line 12 so as to enable the members of the nose of the pliers, when they are expanded, to get adequate purchase and to keep the pliers from slipping in opening 18, thereby avoiding the possibility of fracturing the material only at one side of rupture-opening 18.

The feature of providing a combined finger guard and auxiliary deflecting surface X shown in the several forms of the invention, and indicated by way of example in Figs. 1, 3 and 5—whereby prong 15, if outwardly misdirected, will be deflected by said combined finger guard and deflecting surface so that prong 15 will enter through opening 14 of tongue 13—is not claimed in the present application but forms the subject

matter of a prior application, Ser. No. 117,219, filed September 22, 1949.

I claim:

In a seal of sheet material comprising two connected main sections movable toward one another on a bending line located where they are connected together, and having means adjacent their free ends to interengage when closing the seal, one of said main sections having inner and outer curved surfaces, and the other 10 of said main sections having substantially flat inner and outer surfaces, said main sections

being provided with a rupture-opening that spans said bending line intermediate the ends of the latter, said opening tapering at opposite ends in a direction at right angles to said bending line, a portion of the material of the substantially flat main section being outwardly raised to form a hood adjacent one end of said rupture-opening (to admit the insertion of a tool for the purpose of rupturing the seal) on the bending line.
